(57) **CLAIM**

We claim the ornamental design for a handheld electronic device, as shown and described.

DESCRIPTION

FIG. 1 is a front perspective view of a handheld electronic device;

FIG. 2 is a front elevational view of the handheld electronic device of FIG. 1;

FIG. 3 is a back elevational view of the handheld electronic device of FIG. 1;

FIG. 4 is a left elevational view of the handheld electronic device of FIG. 1;

FIG. 5 is a right elevational view of the handheld electronic device of FIG. 1;

FIG. 6 is a top plan view of the handheld electronic device of FIG. 1; and,

FIG. 7 is a bottom plan view of the handheld electronic device of FIG. 1.
